UNITED STATES PATENT OFFICE.

CHARLES LONGENECKER, OF SPRINGFIELD, MASSACHUSETTS, ASSIGNOR TO QUIGLEY FURNACE & FOUNDEY COMPANY, A CORPORATION OF MASSACHUSETTS.

APPARATUS FOR FEEDING FINELY-DIVIDED FUEL.

1,145,905.

Specification of Letters Patent. Patented July 13, 1915.

Application filed April 29, 1914. Serial No. 835,286.

To all whom it may concern:

Be it known that I, CHARLES LONGENECKER, a citizen of the United States of America, residing at Springfield, county of 5 Hampden, State of Massachusetts, have invented certain new and useful Improvements in Apparatus for Feeding Finely-Divided Fuel, of which the following is a specification.

10 My invention relates to apparatus for feeding pulverized coal or other finely divided fuel to furnaces and is more particularly designed to widen the scope of control of the quantity of fuel which can be so 15 fed to a furnace through one inlet opening.

In certain types of furnaces it is essential that all the fuel to be fed to them shall be delivered through one opening and as the fuel controllers now used with pulverized 20 fuel have a limited range of adjustment of the quantity of fuel delivered by them and also a limited capacity, it has heretofore been difficult if not impossible, to use pulverized fuel on furnaces of this type, which, 25 when running at the maximum capacity require a supply of fuel in excess of the capacity of one controller or feeding device. It is not permissible in cases of this kind as before stated, to connect two or more separate fuel controllers to the one furnace 30 through separate fuel inlets, and it has been difficult if not impossible to so connect two or more separate fuel controllers that they may operate singly or in conjunction and 35 always deliver the fuel in a proper manner to the furnace. I have overcome this difficulty by my invention and improved construction, the best embodiment of which at present known to me is illustrated in the 40 accompanying two sheets of drawings in which—

Figure 1, is a plan view of the apparatus with parts broken away, the fuel hoppers removed and showing a portion of the furnace 45 wall in cross section; Fig. 2 is a central, vertical, longitudinal section on line 2, 2, of Fig. 1, and Fig. 3, is a vertical cross section on line 3, 3, of Fig. 1.

Throughout the drawings like reference 50 characters indicate like parts.

1, represents a portion of the furnace wall having fuel inlet 2. A fuel discharge conduit 3, adapted to deliver a current of air carrying finely divided fuel in suspension,

passes through said inlet. This discharge 55 conduit 3, preferably has a cylindrical portion 16, of larger diameter connected to the discharge end of the conduit by a tapering portion 17. The inlet end of the cylindrical portion 16, of this conduit has an end wall 60 or cover 23, with a central opening through which passes the supplemental air conduit 4. This supplemental air conduit is preferably arranged concentrically with the fuel discharge conduit and preferably has a tapered 65 nozzle portion 24, which extends through the cylindrical portion 16, of the discharge conduit.

19, represents a portion of a water jacket 70 for the fuel discharge conduit.

5, 5, represent two fuel controllers of the general type shown in U. S. Patent No. 784,307, to J. V. Culliney, dated March 7, 1905, which are separately connected to the fuel discharge conduit 3, by delivery pipes 75 or conduits 14, 14. As shown, these conduits extend to inlet openings in the cylindrical walls of the portion 16, of the fuel discharge conduit and are adapted to deliver their contents into the annular mixing chamber 15, formed between the walls 16, of the fuel discharge conduit 3, and the exterior of the supplemental air conduit section 24, in a direction substantially tangential to said walls. The construction of 80 the fuel controllers 5, 5, constitutes no part of my invention, but I will briefly describe their various parts as follows: 6, represents a hopper for the receipt and holding of bodies of finely pulverized coal, which is 85 set on each fuel controller when in operation. 7, 7, are electric motors which drive conveyor screws 9, 9, through gearing concealed in the housings 8, 8. These conveyor screws force regulated quantities of pulverized coal from the bottom of each hopper 90 out over the vertical shafts or compartments 12, 12, through which the pulverized coal falls. 13, 13, are compressed air supply tubes which enter the controllers at one side 100 of the vertical compartments 12, 12, and the currents of air forced through the same pass out by the oppositely disposed fuel delivery tubes 14, 14, carrying with them as much of the finely divided fuel as they can 105 entrain. The surplus of the pulverized coal falls to the bottom of the compartments 12, 12, from which it is returned by the return

conveyer screws 10, 10, to the conveyer screws 9, 9. The screws 10, are driven from the screws 9, by gearing 11, 11.

Such being the construction of the apparatus, the operation is as follows: The motors being set in operation the conveyer screws deliver a regulated amount of pulverized coal to the upper ends of the vertical compartments 12, 12, through which the coal falls as above described, and the regulated amount of compressed air being supplied through tubes 13, 13, the desired quantity of this falling fuel is diverted from its downward path and blown through the delivery tubes 14, 14, to the annular mixing chamber 15. Here the fuel and air are given a spiral motion through said annular mixing chamber out into the tapered portion 17, of the fuel discharge conduit and then through its discharge end into the furnace through the inlet 2. With this is mixed the necessary amount of supplemental air delivered through the supplemental air conduit 4, to supply the necessary amount of oxygen for complete combustion of the fuel in the furnace.

While the amount of fuel delivered by each controller can be regulated within limits by regulating the quantity of compressed air supplied through tubes 13, 13, it is practically impossible to extend this regulation beyond a one hundred per cent. variation of the minimum capacity. That is to say, if the minimum capacity of one fuel controller is 400 pounds, per hour, the maximum capacity cannot be more than 800 pounds per hour in practice. As a large puddling furnace may require as much as 1600 pounds of coal, per hour, at some times, and yet require as little as 400 pounds per hour at other times, it is evident that one controller cannot supply such a furnace at all times, but when my invention is used both controllers may be operated when the requirements of the furnace are between 800 and 1600 pounds of fuel per hour and one of these controllers shut down when the consumption of the furnace drops below 800 pounds per hour. Whether one or both of the controllers are operating the compressed air and fuel delivered from either or both are so taken care of in the annular mixing chamber 15, that there is no variation in the uniform distribution of the fuel through the volume of air supplied either from the controllers or from the supplemental air conduit and there is no interference with the even operation of the furnace at any rate of fuel supply. This even mixture of air and fuel is largely due to the spirally whirling motion set up in mixing chamber 15.

While I have shown only two fuel controllers connected up to the discharge conduit, it is evident that a plurality of such controllers could be employed all connected

to the discharge conduit in a similar manner and delivering their respective fuel supplies into the mixing chamber 15, in a direction substantially tangential to the walls thereof without in any way interfering with the action of one another or disturbing the uniformity of the fuel and air mixture delivered to the furnace and without creating any eddies in the passageways which might produce a deposit of the fuel such as would clog up the apparatus.

Having described my invention, I claim:

1. In an apparatus for feeding finely divided fuel, the combination of a fuel discharge conduit having a substantially circular interior cross section at and near the fuel inlet thereto, two fuel controllers, and separate fuel delivery conduits extending from the said controllers and discharging into the discharge conduit along lines approximately tangential to the circular walls of said conduit.

2. In an apparatus for feeding finely divided fuel, the combination of a fuel discharge conduit having a substantially circular interior cross section at and near its inlet end, and two inlet openings through its walls near said inlet end, a cover for said inlet end provided with a central opening, a supplemental air conduit entering the discharge conduit through said central opening and projecting into the same beyond the before mentioned inlet openings, and means for delivering currents of compressed air and suspended fuel through said inlets in directions substantially tangential to the interior walls of the discharge conduit.

3. In an apparatus for feeding finely divided fuel, the combination of a fuel discharge conduit having a substantially circular interior cross section at and near its inlet end, and two inlet openings through its walls near said inlet end, a cover for said inlet end provided with a central opening, a supplemental air conduit entering the discharge conduit through said central opening and projecting into the same beyond the before mentioned inlet openings, fuel delivery tubes connecting to said inlet openings and discharging into the annular chamber formed between the exterior wall of the supplemental air conduit and the interior wall of the discharge conduit on lines substantially tangential to said walls, and separate fuel controllers connected one to each of the before mentioned fuel delivery tubes.

4. In an apparatus for feeding finely divided fuel, the combination with a discharge conduit of substantially circular interior cross section having an opening at its outer end and provided with a second opening in its circular wall and a conduit connected thereto extending substantially tangentially to said circular wall, of a fuel delivery connection to said last mentioned conduit, means

for delivering therethrough a current of air mixed with finely divided fuel, and a supplemental air conduit connected to the outer end of the discharge conduit and extending thereinto beyond the fuel inlet opening.

5. In an apparatus for feeding finely divided fuel, the combination with a discharge conduit of substantially circular interior cross section having an opening at its outer end and provided with a second opening in its circular wall and a conduit connected thereto extending substantially tangentially to said circular wall, of a fuel delivery connection to said last mentioned conduit, means for delivering therethrough a current of air mixed with finely divided fuel, and a supplemental air conduit connected to the outer end of the discharge conduit and extending thereinto beyond the fuel inlet opening, said supplemental air conduit terminating in a tapering nozzle.

6. A device for feeding finely divided fuel comprising in combination, a discharge conduit of circular cross section having a

tapering portion near the discharge end and a cylindrical portion at and near the inlet end, a cover for the inlet end having a central circular opening, a supplemental air conduit having a tapering nozzle entering 30 said opening and extending through the cylindrical portion of the discharge conduit, and two fuel delivery tubes passing through the cylindrical walls of the discharge conduit in directions substantially tangential 35 thereto.

7. In an apparatus for feeding finely divided fuel, the combination with a discharge conduit adapted to be connected with a furnace, of a supplemental air supply 40 conduit connected to the discharge conduit, and two fuel controllers adapted to deliver currents of compressed air with finely divided fuel suspended therein, having separate connections to said discharge conduit 45 arranged tangentially thereto.

CHARLES LONGENECKER.
